AUTOMATIC INJECTOR

Eugene P. Wise, Kansas City, Mo., assignor of
one-half to Paul L. Stolz, Kansas City, Mo.

Application September 8, 1947, Serial No. 772,688

7 Claims. (Cl. 210—40)

1

This invention relates generally to a device for automatically admixing fluids and more particularly to an injector adapted for attachment to a liquid conduit and having means responsive to a flow of liquid therethrough for injecting a predetermined quantity of fluid into said flow of liquid.

The most important object of this invention is the provision of an automatic injector having a hollow housing provided with means to interpose the same in a stream of flowing liquid and having a rotatable impeller therein operable by said flow of liquid, said impeller being provided with pump means operable upon rotation thereof for injecting a chemical automatically into the liquid within the housing.

Another important object of this invention is the provision of an automatic injector having a rotatable impeller provided with a plurality of pump assemblies therein and operable thereby for receiving a quantity of fluid from within the impeller and ejecting the same into the aforesaid stream of liquid within the housing.

A further object of this invention is the provision of an automatic injector having an impeller provided with a hollow chamber and a plurality of pumps within said chamber, said pumps each including a cylinder and a piston operable to be placed alternately into communication with the hollow chamber and the housing within which the impeller is mounted for receiving a fluid from the impeller and ejecting the same into the housing.

Other objects of this invention include the manner in which the speed of rotation of the aforesaid impeller is controlled by a jet assembly, the latter of which controls the amount of fluid ejected by the pumps; the way in which a bypass is formed to further control the speed of rotation of the impeller when the injector is mounted in a relatively large conduit; the way in which the impeller is provided with a number of freely swingable vanes; the manner in which the entire impeller mechanism is eccentrically mounted within the housing; and the way in which the pump assembly is operated by rotation of the impeller through an eccentric, the latter of which is rotatably secured to a pipe which is arranged to supply the impeller with the chemical to be injected.

Many minor objects will be made clear or become apparent during the course of the following specification, reference being had to the accompanying drawing, wherein:

Fig. 1 is a substantially central sectional view

2

of an automatic injector made in accordance with my present invention, parts thereof being broken away for clearness.

Fig. 2 is a cross sectional view taken on irregular line II—II of Fig. 1; and

Fig. 3 is a fragmentary enlarged cross sectional view taken on line III—III of Fig. 2 and looking in the direction of the arrows.

It is common knowledge that oftentimes it becomes necessary and quite desirable to inject chemicals of one form or another into a conduit having a flow of liquid therein under pressure. Specific examples include the field of fire prevention wherein the supply of water for extinguishing the fire should be supplied with a chemical that will aid in such fire extinguishing operation.

Many times it is necessary to inject a solvent into such stream of water or water softening solutions of one form or another.

In the drawing, a hollow housing broadly designated by the numeral 10 is provided with a plate 12 having a number of perforations (not shown) formed therein to serve as a means for mounting the entire assembly.

This housing 10 has an inlet port 14 and an outlet opening 16 formed therein, said openings communicating with a pair of substantially parallel conduits 18 and 20 respectively. These conduits 18 and 20 communicate at their innermost end with the interior of the housing 10, as clearly illustrated in Fig. 1. The housing 10 has a neck portion 22 extending laterally from one face thereof for rotatably receiving an extended hub 24 of an impeller, broadly designated by the numeral 26. The opposite face of the housing 10 has a plate 28 removably secured thereto through the medium of a plurality of screws or the like 30.

This impeller 26 has a hollow chamber 32 formed therein defined by a pair of substantially parallel walls 34 and 36, the latter of which is removably secured to an annular wall 38 by a number of screws 40. The hub 24 of the impeller 26 extends laterally from the outermost face of the wall 34 and has a longitudinal bore 42 formed therethrough. This bore 42 communicates with the interior of the chamber 32 at one end thereof and receives a pipe 44 that is threaded into the neck 22 of the housing 10 as at 46. A lock nut 48 is also threaded upon the pipe 44 exteriorly of the housing 10 to hold pipe 44 against rotation. The pipe 44 extends a distance into the chamber 32 of the impeller 26 and has a portion thereof formed polygonally in

55

cross section as shown in dotted lines in Fig. 1, to receive a disc 50 having a similarly contoured opening, the latter of which is held against displacement by a nut 52. A pin 54 integral with the disk 50 extends laterally from one face thereof and into the chamber 32 for receiving a plurality of pistons 56. These pistons 56 form a part of a number of pump assemblies designed to inject a fluid from the chamber 32 into the housing 10 as hereinafter more fully described.

Any number of these pump assemblies may be utilized, there being three shown disposed 120° apart within the chamber 32.

One end of each of the pistons 56 has a ring 58 formed thereon and loosely receiving the laterally extending pin 54 on the disk 50. The opposite ends of the pistons 56 are circular in cross section and extend into a cylinder 60. These cylinders 60 are T-shaped as shown in Fig. 2, one leg thereof being hollow for slidably receiving the pistons 56 and the other two legs being secured to the impeller 26.

The innermost face of the wall 34 of the impeller 26 has a cavity 62 formed therein adjacent the annular wall 38 of impeller 26 for journaling the free end of one of the other legs of the cylinder 60. The leg of the cylinder 60 opposite to the said leg that is journaled in the cavities 62, is freely mounted within a bearing 64 having connection to the annular wall 38 by bolts 66.

It is thus seen that as the impeller 26 is caused to rotate, the pistons 56 will reciprocate within the tubular portion of the cylinders 60 and these cylinders 60 will each oscillate in the manner shown by dotted lines in Fig. 3. A number of cavities 68 are formed within the annular wall 38 of the impeller 26 opening outwardly for receiving a like number of fins 70. These fins 70 have a circular portion 72 formed thereon, said portions 72 being freely rotatable within the cavity 68 of the wall 38. It is preferable that the portion 72 of the fins 70 be about two-thirds encased by the cavities 68 to the end that the fins 70 are freely swingable within the housing 10 and yet are held against displacement from the cavities 68. Fins 70 have a width substantially the same as the width of the housing 10 and said housing serves to hold such fins 70 against any tendency of the same to slide transversely within the cavity 68.

As clearly illustrated in Fig. 1, the impeller 26 is eccentrically mounted within the housing 10. The distance between the outermost face of the annular wall 38 and the innermost face of the housing 10 progressively increasing from the innermost end of the inlet conduit 18 and again progressively decreasing as the innermost end of the outlet conduit 20 is approached. The fins 70 are thus kept in action by centrifugal and gravitational forces and as these fins 70 approach the normally uppermost end of the housing 10, the same will be folded back into notches 74 formed in the annular wall 38 of the impeller 26.

A pair of packing members 76 are mounted within the bore 42 of the hub 24 and held in spaced apart relationship through the medium of a spring 78. This spring 78 bears against a pair of washers 80 and is disposed in circumscribing relationship to the pipe 44 as are the packing elements 76 and the washers 80. A plug 82 threaded into the bore 42 at the outermost end thereof serves to hold the entire packing unit in place. One end of the cylinders 60 extends into a cavity 84 formed in the annular wall

38 of the impeller 26 and has an outlet opening 86 formed therein.

A port 88 formed in the wall 38, places the cavity 84 into communication with the chamber 32 of the impeller 26 and a second port 90 is disposed in the annular wall 38 to place the cavity 84 into communication with the housing 10.

A jet for the port 90 constitutes a removable perforated plug 92. This plug 92 is threaded into the annular wall 38 of the impeller 26 in communication with the outlet end of the port 90. Upon rotation of the impeller 26 and consequent swinging movement of the cylinder 60 in the manner shown by dotted lines in Fig. 2, the outlet opening 86 formed in the cylinder 60 will alternately communicate with the ports 88 and 90.

It is clear that liquid entering the inlet port 14 will impinge upon the vanes 70 of impeller 26 causing rotation thereof which will in turn operate the pump assemblies which include the pistons 56 and cylinders 60. The impeller 26 is freely rotatable on the pipe 44 within the housing 10 and the neck 22 thereof. A centering pin 94 extends through the plate 28 of the housing 10 and a distance into the plate 36 of the impeller 26 to cooperate with the hub 24 in holding impeller 26 in centered relationship with respect to the neck 22 of housing 10.

30 A by-pass, broadly designated by the numeral 96, includes a pair of conduits 98 and 100. These conduits 98 and 100 are preferably formed integrally with the housing 10 and the conduit 98 is directly connected with the inlet opening 14 of the housing 10. One end of this conduit 98 has an elbow 102 threaded thereinto, the latter of which connects with a nipple 104. In mounting the entire assembly within a water line 106, a T 108 is interposed within this line 106 on one 40 side of a valve 110, said T 108 having connection with the nipple 104. An opening 112 is formed in the conduit 98 to place the same in communication with the conduit 100, the latter of which communicates with the outlet opening 16 of the housing 10 near one end thereof. An elbow 114, a nipple 116 and a T 118, the latter of which is interposed in the line 106 on the opposite side of the valve 110, all serve as a means for placing the housing 10 and the conduit 100 into communication with the line 106.

55 A piston 120 freely slidable within the conduit 98 is normally disposed to close the opening 112 of the conduit 98. This piston 120 is held in such a position by spring 122 interposed between one end of piston 120 and a plug 124, the latter of which closes the end of conduit 98 opposite to the elbow 102.

In operation, the injector just described is mounted within the line 106 as just above set forth. The valve 110 is closed causing liquid within the line 106 to flow into the housing 10 by way of the T 108, the nipple 104, the elbow 102, inlet opening 14 and passage-way 18. The force of such liquid flowing through the passage-way 65 18 will cause rotation of the impeller 26 as the same comes into contact with the fins 70. As impeller 26 thus rotates, the cylinders 60 will be carried therewith in a circular path of travel causing the hollow portion thereof to reciprocate upon the respective pistons 56. As these cylinders 60 so reciprocate, they will swing as illustrated in Fig. 3 bringing the opening 86 thereof into alternate communication with the ports 88 and 90. The pipe 44 and the chamber 32 of the impeller 26 constitute a continuous conduit for in-

troducing a fluid from a source not shown. In other words, one end of the pipe 44 has communication with a source of such fluid while the opposite end thereof is in direct communication with the interior of the chamber 32. Such fluid passing through the pipe 44 is kept under pressure to the end that the chamber 32 remains full at all times and when the openings 80 of the cylinders 60 are in communication with the respective ports 88, the pumping action of the cylinder 60 and pistons 56 will draw such fluid into the cylinders 60 through the port 88 and opening 86. When the cylinders 60 and pistons 56 swing in the opposite direction, the port 86 will be moved into communication with the opening 90 and the fluid within the cylinder 60 will be ejected into the housing 16 and into the flow of liquid therein through the jet plug 92.

The flow of water within the housing 10, together with the fluid that has thus been ejected thereinto, will then flow out of the passage-way 18 and into the conduit 100, elbow 114, nipple 116, T 118 and thence into the line 106. It is to be noted that the speed of rotation of the impeller 26 and thereby the amount of liquid that is injected into the flow of water, depends partially upon the pressure within the line 106. The speed of rotation of impeller 26 is further governed by the size of the jet 92. In other words, a plug 92 having a relatively small restricted opening therein, will tend to hold back the flow of fluid passing from the cylinders 60 through openings 86 and thereby retard the speed of rotation of impeller 26. Oftentimes the injector will be inserted into relatively large lines 106 which would normally cause a fast rotation of the impeller 26 and injection of more fluid into the stream of water than is desired. When this pressure becomes too great, the by-pass 96 will function to direct a part of the flow of water directly into the conduit 100 by the action of the piston 120. This by-passed flow of water will act upon the piston 120 to move the same against the spring 122 and thereby moving piston 120 to an open position with respect to the opening 112. It is clear that adjusting of the tension of spring 122 will control the amount of water that is allowed to by-pass through the conduits 98 and 100.

It is apparent from the foregoing that the injector assembly just described is entirely automatic and that the desired amount of chemical solution or other fluid that is injected into the flow of water through the pipe 44, may be controlled to virtually any degree desired. A relatively large amount of chemical may be injected by increasing the size of the plug 92 and/or increasing the tension on spring 122. If only a small amount of solution is desired, then the spring 122 should have little tension and a plug 92 having a very small opening therethrough should be used.

Although only one form of my invention has been illustrated and described, it is to be understood that many changes and modifications may be made particularly with respect to details of construction without departing from the spirit of this invention or scope of the appended claims.

Having thus described the invention, what is claimed as new and desired to be secured by Letters Patent is:

1. An automatic injector of the character described comprising a hollow housing having an inlet opening and an outlet opening; a hollow rotatable impeller in said housing responsive to a flow of liquid passing through the housing from

said inlet opening to said outlet opening, said impeller having an inlet port and at least one outlet port; a conduit connected with said inlet port to direct a fluid into said impeller; and means operable within said impeller and connected for rotation thereby for feeding said fluid from the impeller through said outlet port to said flow of liquid in the housing as the impeller rotates.

2. An automatic injector of the character described comprising a hollow housing having an inlet opening and an outlet opening; a hollow rotatable impeller in said housing responsive to a flow of liquid passing through the housing from said inlet opening to said outlet opening, said impeller having an inlet port and at least one outlet port; a conduit extending into the impeller through said inlet port to direct a fluid into said impeller; and means rotatably mounted on said conduit within said impeller and connected for rotation thereby for feeding said fluid from the impeller through said outlet port to said flow of liquid in the housing as the impeller rotates.

3. An automatic injector of the character described comprising a hollow housing having an inlet opening and an outlet opening; a hollow rotatable impeller in said housing responsive to a flow of liquid passing through the housing from said inlet opening to said outlet opening, said impeller having an inlet port and at least one outlet port; a conduit connected with said inlet port to direct a fluid into said impeller; and means within said impeller and connected for rotation thereby for feeding said fluid from the impeller through said outlet port to said flow of liquid in the housing as the impeller rotates, said means comprising at least one pump assembly operable to alternately draw a predetermined quantity of fluid from said impeller and eject the same into the flow of liquid.

4. An automatic injector of the character described comprising a hollow housing having an inlet opening and an outlet opening; a hollow rotatable impeller in said housing responsive to a flow of liquid passing through the housing from said inlet opening to said outlet opening, said impeller having an inlet port and at least one outlet port; a conduit connected with said inlet port to direct a fluid into said impeller; means within said impeller and connected for rotation thereby for feeding said fluid from the impeller through said outlet port to said flow of liquid in the housing as the impeller rotates, said means comprising at least one pump assembly operable to alternately draw a predetermined quantity of fluid from said impeller and eject the same into the flow of liquid; and jet structure in said outlet port for limiting the amount of fluid ejected by said pump.

5. An automatic injector of the character described comprising a hollow housing having an inlet opening and an outlet opening; a hollow rotatable impeller in said housing responsive to a flow of liquid passing through the housing from said inlet opening to said opening, said impeller having an inlet port and at least one outlet port; a conduit connected with said inlet port to direct a fluid into said impeller; means within said impeller and connected for rotation thereby for feeding said fluid from the impeller through said outlet port to said flow of liquid in the housing as the impeller rotates, said means comprising at least one pump assembly operable to alternately draw a predetermined quantity of fluid from said impeller and eject the same into the flow of

liquid; and jet structure in said outlet port for limiting the amount of fluid ejected by said pump, the speed of rotation of said impeller being controlled by the size of said jet structure.

6. An automatic injector of the character described comprising a hollow housing having an inlet opening and an outlet opening; a hollow rotatable impeller in said housing responsive to a flow of liquid passing through the housing from said inlet opening to said outlet opening, said impeller having an inlet port and at least one outlet port; a conduit connected with said inlet port to direct a fluid into said impeller; and means within said impeller and connected for rotation thereby for feeding said fluid from the impeller through said outlet port to said flow of liquid in the housing as the impeller rotates, said means comprising at least one pump assembly operable to alternately draw a predetermined quantity of fluid from said impeller and eject the same into the flow of liquid, said pump including a cylinder having a reciprocable piston mounted therein, one end of the piston being rotatably mounted separately from the impeller and eccentrically with respect to the axis of impeller rotation.

7. An automatic injector of the character described comprising a hollow housing having an inlet opening and an outlet opening; a rotatable impeller in said housing, said impeller having a hollow chamber and being responsive to a flow of liquid passing through said housing from the inlet

5
10
15
